United States Patent Office

Des. 183,099
Patented June 24, 1958

183,099

WEIGHING SCALE

Harold Lawrence King, Mount Vernon, N. Y.

Application May 20, 1957, Serial No. 46,231

Term of patent 3½ years

(Cl. D52—10)

Fig. 1

Fig. 2

Fig. 3

Fig. 4

Figure 1 is a front perspective view of a weighing scale, showing my new design;

Figure 2 is a plan view thereof;

Figure 3 is a right side elevational view thereof;

Figure 4 is a rear elevational view thereof.

I claim:

The ornamental design for a weighing scale, substantially as shown.
